UNITED STATES PATENT OFFICE.

ALEXANDER BOYNTON, OF SAN ANTONIO, TEXAS.

FLOWING DEVICE FOR OIL WELLS.

Application filed November 8, 1922. Serial No. 599,695.

To all whom it may concern:

Be it known that I, ALEXANDER BOYNTON, a citizen of the United States, and resident of San Antonio, in the county of Bexar and State of Texas, have invented certain new and useful Improvements in Flowing Devices for Oil Wells, of which the following is a specification.

This invention relates to flowing devices especially adapted for use in oil wells.

Briefly stated an important object of this invention is to provide a flowing device by means of which the well is caused to flow by heads and wherein the pressure of the gas is utilized as a means to facilitate the flow of oil.

A further object is to provide a flowing device which may be readily adjusted for use under a variety of conditions.

A further object is to provide a flowing device for oil wells which is of highly simplified construction, efficient in use and cheap to manufacture.

Other objects and advantages of the invention will be apparent during the course of the following description.

In the accompanying drawing, forming a part of this application and in which like numerals are employed to designate like parts throughout the same,

Figure 1 is an elevation of the improved flowing device in use.

Figure 2 is a group perspective of the same.

Figure 3 is a side elevation of the improved flowing device detached.

Figure 4 is a vertical sectional view through the device.

Figure 5 is a horizontal sectional view taken on line 5—5 of Figure 4.

Figure 6 is a side elevation illustrating a modified form of invention.

Figure 7 is a vertical sectional view through the same.

Figure 8 is a horizontal sectional view taken on line 8—8 of Figure 7.

Figure 9 is a side elevation of a further modification of the invention.

Figure 10 is a vertical sectional view through the device illustrated in Figure 9.

Figure 11 is a horizontal sectional view taken on line 11—11 of Figure 10.

Figure 12 is a perspective of a movable valve illustrated in Figure 7.

Figure 13 is a perspective of a valve illustrated in Figure 10.

In the drawing the numeral 5 designates a string of tubing arranged as illustrated in Figure 1 within the casing 6 and the lower portion of the string of tubing has connection with the improved flowing device by means of which the oil is caused to flow by heads.

In carrying out the invention the lower end of the string of tubing 5 is threaded into the upper end of a tubular body 10 and the upper end of the string of tubing has connection with a discharge pipe 11 which communicates with the usual tank 12. Figure 1 illustrates that the upper portion of the tubing 5 is provided with a valve 12 which may be released for permitting the accumulated gas and oil to be discharged into the tank at the proper intervals. The improved flowing device consists of the body 10, the lower end of which is interiorly screw threaded as indicated at 13 for the reception of a supporting pipe 14 which extends to the bottom of the well and thereby spaces the flowing device from the bottom of the well. With reference to Figure 1 it will be observed that the supporting pipe has its lower end closed by a plug 15 or other suitable means so that mud and sediment cannot enter the lower portion of the pipe and possibly interfere with the operation of the several valves to be fully herein-after described.

However, that portion of the supporting pipe 14 immediately beneath the flow device is formed with a plurality of perforations or inlet openings 16 through which the oil passes. Should the string of tubing become parted intermediate its ends the supporting pipe 14 will prevent it from dropping in the well.

Figures 2 and 4 illustrate that the intermediate portion of the tubular body 10 is formed with an annular valve seat 20 with which an oil retaining valve 21 is associated and the said valve 21 is mounted on a stem 22 movable longitudinally through the tubular body.

The stem 22 is slidable through and is guided by a depending tubular guide 24 supported by means of radial wings 25 and the guide 24 also serves as an abutment for one end of a coiled spring 27, the purpose

of which is to normally hold the valve in its seated position. One end of the coiled spring 27 contacts with one end of the guide 24 and the other end of the spring contacts 5 with the flange 29 of a nut 30 threaded on the stem. It might be stated that the nut 30 is held in a set position by means of a jam nut 32 also held on the stem by means of threads. In practice the coiled spring is 10 tensioned so that the oil retaining valve 21 will resist 100 lbs. or more to the square inch and consequently the pressure of the oil beneath the valve cannot unseat the same.

The stem 22 is formed above the oil retaining valve 21 with a second valve 36 which might be said to be a flow valve and this flow valve is associated with an annular upstanding seat 37. However, it is important to note that the flow valve 36 is not 15 seated on the seat 37 but is spaced from four to ten thousandths of an inch so as to equalize the gas pressure on both sides of the same for a purpose to be hereinafter specified. The flow valve 36 is held in position by a nut 40 having radial wings 41 by means of which the nut may be turned and the wings 41 also serve as a guide to direct the vertical movement of the stem. The bore of the body 10 between the annular 20 valve seat 37 and the upper screw threads is of a uniform diameter and consequently the radial wings will not bind, when moved vertically.

Attention is directed to Figure 1 wherein 25 it illustrates that a separator pipe 50 is threaded onto the intermediate portion of the body and is spaced from the tubing 5. The separator pipe extends for two or three hundred feet above the flowing device and 30 is open at the top thereby forming a partition or separator between the oil and the gas as the same are produced by the well. That is to say the gas being lighter than the oil will rise to the upper end of the separator 35 pipe 50 and when the upper portion of the casing is filled the gas will move downwardly in the separator pipe.

The oil produced by the well does not rise 40 to the open upper end of the separator pipe and consequently cannot enter the flowing device by way of the separator pipe and in any way interfere with the operation of the device.

The gas produced by the well is temporarily 45 confined within the casing by means of the casing head 51 and the valve 12' and consequently the gas which enters the separator pipe moves downwardly on the outside of the tubing and enters the tubular body 50 by way of a plurality of gas inlet openings or ports 53. The gas which enters the body 10 by way of the ports 53 enters the tubing 5 as the valve 36 is maintained in its unseated position.

However at the proper time the valve 12'

is opened and the gas which is under a considerable pressure rushes through the tubing and contacts with the recessed under side of the flow valve 36 and thereby elevates the valve. When the valve 36 is thus elevated the stem 22 is moved upwardly for unseating the valve 21. With reference to Figure 4 it will be observed that the oil which passes the seat 20 enters an atomizing chamber 55 and is atomized by the gas rushing through the ports 53. This causes the liquid to pass upwardly through the tubing and into the tank and the mixture of the gas and oil forms an additional gas which greatly facilitates the discharge of the products of the 80 well.

In summarizing it might be stated that the improved flowing device is intended to make small oil wells flow by heads, the flowing intervals being regulated to best suit 85 each particular well by means of an automatic gas release valve at or near the casing head. In practice the flowing device is placed near the bottom of the well below the top of the last producing sand and the supporting pipe 14 will space the oil inlet openings 16 from the mud and sediment in the bottom of the well.

As the well produces oil and gas the oil 90 rises on the outside of the partition or separator pipe and as previously stated the gas will enter the separator pipe 50 and then enter the string of tubing 5 so that when the valve 12 is operated the stem 22 will be elevated whereupon the inrushing gas will 100 vaporize the oil entering the chamber 50.

In the form of the invention illustrated in Figures 6, 7 and 8 the body is designated by the numeral 70 and has its upper end interiorly screw threaded for the reception of 105 a bushing 71 by means of which the flowing device may be connected to the tubing.

The lower portion of the body may be 110 interiorly or exteriorly screw threaded as indicated at 73 for engagement with the supporting pipe 74. That portion of the supporting pipe 74 immediately beneath the body is provided with a suitable number of openings 75 through which the oil may enter and as previously stated the openings in the pipe are a substantial distance above the bottom of the well so that mud and sediment cannot enter the flowing device and interfere with the operation of the same.

Figure 7 illustrates that the flowing device 115 is formed with an inwardly directed projection constituting an annular shoulder or valve seat 76 with which an oil retaining valve 77 is associated. The valve 77 is mounted on a stem 79 movable centrally 120 through the body 70 immediately beneath a flow valve 80. The flow valve 80 is associated with and is spaced from contact with a flow valve seat 81 formed at a point above 125 the valve seat 76. In carrying out the in- 130

vention the flow valve 80 is threaded on the stem and is held in a set position by means of a nut 84 also threaded on the stem. It will be observed that the seat 76 and the valve 77 prevent the flow valve 80 from seating on the portion 81 and consequently the gas pressure on both sides of the flow valve is substantially the same.

The flow valve 80 is formed with a guide sleeve 83 which slidably receives a depending lug or projection 84' formed on the bushing 71 and the said sleeve is formed with a suitable number of openings 85. The sleeve 83 not only serves as a guide for the valve but also forms an enclosure for a coiled spring 86 which urges the valve 77 into engagement with the seat 76. Figure 7 illustrates that the upper portion of the coiled spring 86 is engaged by a follower 87 which in turn is held in a set position by set screws 88 threaded through the bushing. By an adjustment of the set screws 88 the tension of the coiled spring may be varied.

In this form of the invention the body is provided with an atomizing chamber 90 and with an annular series of openings 91 which permit the gas within the separator pipe to enter the body and the tubing. At the proper moment the outlet valve is opened and the gas under pressure will flow into the atomizing or vaporizing chamber 90 and elevate the flow valve 80 whereupon the oil retaining valve 77 will be unseated. This permits oil to enter the vaporizing chamber 90 and mix with the inrushing gas. This forms additional gas which flows up through the body and through inclined openings 93 into the tubing and then into the tank. The stem 79 is not only guided by the sleeve 83 but by a plurality of radial wings 96 formed beneath the valve 77 and the wings contact with the side walls of the valve seat 76. However, the wings 96 do not interfere with the free movement of the oil into the vaporizing chamber 90.

In the form of the invention illustrated in Figures 9, 10 and 11 the body is designated by the numeral 100 and has its upper portion threaded for connection with a bushing 101 and the bushing is in turn connected to the tubing which extends through the casing. The lower portion of the body is in turn connected to a supporting pipe 103 which supports the flowing device a suitable distance above the bottom of the well. Oil inlet openings 104 are provided beneath the flow device and admit oil to the flow device. The valve stem is designated by the numeral 106 and is formed with guide wings 107, and a reduced portion 108 by means of which the valve is properly guided. Figure 10 illustrates that the wings 107 are movable through an inwardly extending annular projection 109 while the reduced stem 108 is movable

through a centrally arranged opening 110 in the bushing 101.

In carrying out this form of the invention the valve 112 contacts with the seat 109 and thereby normally prevents the oil 70 from flowing into the body. The valve 112 and the seat 109 maintain the flow valve 114 off its seat 115 and consequently the pressure of gas on both sides of the flow valve is the same.

The separator pipe or string is connected to the body as indicated at 116 and extends a distance of two or three hundred feet and is open at its upper end for the reception of gas. The gas which enters the separator 80 pipe 118 passes through radial openings 119 in the wall of the vaporizing chamber 120 and the oil which enters the vaporizing chamber passes upwardly beyond the flow valve 114 and through diagonal nozzles 122 85 in the bushing 101. Attention is directed to the fact that the nozzle 122 forms an effective means for atomizing the oil. This is an important feature of the invention.

In the operation of this form of the invention the opening of the valve in the top of the tubing permits the gas to rush in through the openings 119 and contact with the recessed under side of the flow valve 114 for elevating the valve 112. The simultaneous movement of the oil and gas through the vaporizing chamber 120 mixes the oil and gas with a result that additional gas is created, all of which contributes to the movement of the products of the well through 100 the tubing.

However, the valve 112 is normally held in its seated position by means of a coiled spring 130 confined between a nut 132 and the under side of the bushing 101.

The improved flowing device will make any small oil well flow by heads, which is accomplished by keeping the oil and gas separate as the same are produced in the well until such time as the accumulated gas 110 has developed enough pressure and volume to atomize the oil and blow it out of the well, when this gas is released at proper intervals by means of an automatic valve control at or near the casing head of the well. In this invention it is essential that the oil and gas be kept separate until such time as it is desired that the well flow, whereupon the gas is admitted through the inlet openings in the main body. The rush of gas in 120 large volume raises the flow valve, which in turn raises the oil valve. The oil and gas thus meet under high pressure in the atomizing chamber below the flow valve. To the large volume of gas is thus added the impact 125 of the oil passing upward through the atomizing chamber and striking the flow valve. Oil when atomized creates gas in great quantities which augments the flow of gas from the gas chamber and tends to keep the flow 130

valve open. The spring tension which seats the oil valve is so adjusted that the weight of the oil will be resisted by the spring and the oil valve kept seated until the automatic relief at casing head causes the well to flow. In other words, if the separator string is 5 300 feet long, the tension of the spring will be so adjusted as to resist the weight of the column of oil slightly more than 300 feet 10 high. In this manner there is no danger of the oil accumulating on the outside of the separator string or section and flooding the gas chamber by flowing over the top of the separator string. If such flooding should 15 happen the device would fail to work because a solid column of oil would have to be raised by the gas whenever the gas relief valve at the casing head is open. Experience has shown that this can not be done, except in strong gas wells which would ordinarily flow without this device. The purpose of this device is accomplished by retaining the gas and releasing it under high 20 pressure at intervals, and using it to atomize the oil which thus lightens the column 25 to be lifted, and enables the well to throw out the mixed column of oil and gas, whereas the well unaided by this device would be unable to throw out the solid column of oil. 30 Without the aid of this device the well is constantly wasting its gas which bubbles up through the oil and escapes at the casing head. With the aid of this device the gas is conserved until such time as it develops 35 enough power to accomplish the task of lifting the oil out of the well, which task is made easy by mixing the oil with the gas, and atomizing all the oil at the same time, so as to create additional gas. This additional 40 gas and lightened atomized column makes it easy for the accumulated gas to blow the oil from the well at proper intervals. The release valve at the casing head must be so set that the well will flow before 45 it will produce enough oil to flood the flowing device as stated above. This is determined by tests of each well before installing device.

It costs at least \$1000.00 to equip small 50 wells to pump their production. This device together with the automatic gas relief at the casing head can be installed for about one-tenth of the cost of the usual pumping equipment.

The foregoing illustrates that the inventive 55 idea involved in this application is capable of a wide variety of mechanical expressions and it is therefore understood that the several forms of the invention herewith shown and described are merely to be taken as preferred examples of the same and that such minor changes in arrangement and construction of parts may be made as will remain within the spirit of the invention and 60 the scope of what is claimed.

Having thus described the invention, what I claim is:—

1. The combination of a casing, a tubing extending through the casing, and a separator pipe connected to the tubing and having communication with the same and the casing. 70

2. The combination of a casing, a tubing extending through the casing, a separator pipe connected to the tubing and having communication with the same and the casing, and a gas actuated oil retaining valve arranged at the lower portion of said separator pipe. 75

3. The combination of a casing having its upper end closed, a tubing extending through the casing, a control valve arranged at the upper portion of the tubing, and an oil and gas separator pipe surrounding the tubing and having communication therewith and with the casing. 85

4. The combination of a casing having its upper end closed, a tubing extending through the casing, a control valve arranged at the upper portion of the tubing, an oil and gas separator pipe surrounding the tubing and having communication therewith and with the casing, and a gas actuated oil retaining valve arranged at the lower portion of said separator pipe. 90 95

5. A flowing device for wells comprising a body having means whereby the same may be connected to a string of tubing, a stem movable through the body and having an oil retaining valve, said body being formed 100 with a seat engaged by said valve, a flow valve connected to said stem, and a guiding device for said flow valve.

6. A flowing device comprising a body adapted for connection with a string of tubing and having a vaporizing chamber and a plurality of openings communicating with the vaporizing chamber, a valve arranged at the lower end of said vaporizing chamber and adapted for retaining the oil beneath the chamber, a flow valve rigidly connected to said first named valve and adapted for operating the same. 105 110

7. A flowing device comprising a body adapted for connection with a string of tubing and having a vaporizing chamber and a plurality of openings communicating with the vaporizing chamber, a valve arranged at the lower end of said vaporizing chamber, and adapted for retaining the oil beneath the chamber, a flow valve rigidly connected to said first named valve and adapted for operating the same, and spring means normally seating the first named valve. 115 120

8. A flow device comprising a body adapted for connection with a string of tubing and having a vaporizing chamber and a plurality of openings communicating with the vaporizing chamber, a valve arranged at 125 130

- the lower end of said vaporizing chamber and adapted for retaining the oil beneath the chamber, a flow valve rigidly connected to said first named valve and adapted for 5 operating the same, spring means normally seating the first named valve, and a separator pipe connected to said body and terminating a substantial distance above the same.
- 10 9. The construction set forth in claim 8, and means whereby the tension of said spring means may be varied.
- 10 10. The construction set forth in claim 8, said flow valve having its under side formed 15 with a recess.
11. A flow device for wells comprising a body adapted to be interposed in a string of tubing and having a vaporizing chamber and openings communicating with the 20 vaporizing chamber, a valve stem movable through the chamber and having its lower portion formed with a valve, said body being formed with a valve seat engaged by said valve, spring means normally holding 25 the valve in its seated position, a flow valve connected to said stem and arranged at one end of said vaporizing chamber, and a bush-
- ing threaded into said body and having openings communicating with said vaporizing chamber. 30
12. The construction set forth in claim 11, and a separator pipe connected to said body and communicating with said vaporizing chamber.
13. A flow device comprising a body 35 adapted for connection with a string of tubing and having a vaporizing chamber, the opposite ends of said chamber being formed with valve seats, oil retaining and flow valves adapted for engaging said seats, said oil retaining valve constituting a means to maintain the flow valve in an unseated position, a stem connecting the valves, a guide sleeve connected to one of said valves, and a spring engaging one of the valves and 40 enclosed within said sleeve. 45
14. The construction set forth in claim 13, and a bushing threaded onto said body and having openings communicating with said vaporizing chamber. 50
15. The construction set forth in claim 14, and a separator pipe connected to said body.

ALEXANDER BOYNTON.
